DONALD F. WHITING AND HUGH S. TAYLOR, OF BROOKLYN, NEW YORK, ASSIGNEES TO
WESTERN ELECTRIC COMPANY, INCORPORATED, OF NEW YORK, N. Y., A COR-
PORATION OF NEW YORK.

COMMUNICATION SYSTEM.

Application filed December 24, 1924. Serial No. 757,802.

To all whom it may concern:

Be it known that we, DONALD F. WHITING and HUGH S. TAYLOR, citizens of the United States of America, residing at Brooklyn, in the county of Kings and State of New York, have invented certain new and useful Improvements in Communication Systems, of which the following is a full, clear, concise, and exact description.

10 The invention relates to intercommunicating systems, especially systems of the type involving operation of common receiving apparatus from different transmitting stations.

15 An object of the invention is to provide a simple and effective system which will avoid confusion due to simultaneous attempts to transmit, made at different transmitting stations.

20 In the embodiment of the invention specifically illustrated and described herein, operation of means to condition one of the transmitting stations for transmitting speech disable a loud speaking receiver adjacent that transmitting station, in order to suppress side tone, and the operation of means for conditioning another of the transmitting stations for transmitting alarm or telegraphic code signals renders the operated 25 disabling means ineffective, so that the disabled receiver will be conditioned to reproduce the alarm or telegraphic code signals.

The single figure of the drawing is a circuit diagram of a system embodying this 30 form of the invention.

The system there shown comprises telephone transmitting sets such as 1 and 2, only two of which are shown but more of which may be provided, receiver groups such 35 as 3 and 4, only two of which are shown but more of which may be provided, and an amplifier system 5 for connection between any one of the telephone transmitting sets and any desired ones of the receiver groups.

40 The transmitting sets 1 and 2 are located at different places, for instance at different parts of a battleship on which the system may be installed.

The receivers of groups 3 and 4 are preferably loud speaking receivers located in different places, for instance at different parts

of the ship if the system is installed on ship-board.

The receiver group 3 comprises receivers such as 8 and 9, only two of which are shown though more may be provided; and the receiver group 4 comprises receivers such as 10 and 11, only two of which are shown though more may be provided. In the particular apparatus arrangement indicated in the drawing, receivers 8 and 10 are local to the telephone transmitting sets 1 and 2, respectively. That is, the receivers 8 and 10 are intended to represent receivers which, because of their locations relative to transmitters 6 and 7, respectively, or because of other conditions of the operation of the system, might cause objectionable side tone in transmitters 6 and 7, respectively, or cause singing in the system, unless proper precautions were taken to prevent the production of such side tone. Any number of such local receivers may be present in the system, though only one per group is shown.

The amplifier system 5 is shown as a two stage system, the first stage preferably comprising an amplifier 12 of the electron discharge type, and the second stage a push-pull amplifier 13 of the electron discharge type. An input transformer 14 and an input potentiometer 15 are provided for the amplifier 12, the primary winding of the transformer comprising an upper half 16 and a lower half 17. An interstage transformer 18 having a primary winding 19, and an output transformer 20 having a secondary winding 21 are provided for the amplifier system 5. The winding 21 feeds an auto-transformer 22 having output leads 23, 24 and 25 which deliver current to the receivers such as 8, 9, 10 and 11 through circuits traced hereinafter.

A source of electromotive force 26, symbolic of means comprising a battery, D. C. dynamo or the like, supplies filament current for the amplifiers 12 and 13.

A source of electromotive force 27, symbolic of a battery, D. C. dynamo or the like, supplies space current for the amplifiers 12 and 13. A condenser 28 prevents the D. C. from source 27 from reaching the primary winding of the interstage trans-

former 19. In series with the primary winding of transformer 19 is the primary winding 29 of a feed back transformer 30, which has a secondary winding 31. Means are provided, as described hereinafter, for connecting the winding 31 to the primary winding of the transformer 14, to convert the amplifier 12 into a feed back oscillator, for a purpose set forth hereinafter, a condenser 32 being connected across the winding 31 for setting the frequency of oscillation. The winding 29 is normally short circuited by a contact 33 of a normally deenergized relay 34; and the winding 31 is normally short circuited by a contact 35 of the relay 34.

When the amplifier 12 is to be converted into an oscillator as mentioned above, the relay 34 is energized as described hereinafter, to open its short circuiting contacts, 20 and a relay 36 is also energized as described hereinafter. The relay 36 has an armature 37 for changing the setting of the input potentiometer 15, and also has an armature 38. Armature 38 normally closes a gap in 25 a circuit traced hereinafter for supplying D. C. from source 26 to conductors 39 and 40. By the operation of switches as described hereinafter, conductors 39 and 40 together, can be selectively connected to 30 transmitters 6 and 7, for delivering energizing D. C. thereto, and for delivering A. C. from the selected transmitter to the primary winding of transformer 14 over a circuit traced hereinafter. When relay 36 is energized, armature 38 opens its normal contact, 35 and closes its right hand contact to connect the condenser 32 and the secondary winding 31 of the feed back transformer 30 to the primary winding of the input transformer 14, the circuit from condenser 32 and winding 31 extending from the lower side of the condenser and the winding through a conductor 41, the upper half 16 of the primary winding of transformer 14, a part of conductor 39, a conductor 42, right hand contact 45 of armature 38, a conductor 43, the lower half 17 of the primary winding of transformer 14, a condenser 44, and a conductor 45 to the upper side of condenser 32 and 50 winding 31. A condenser 46 permanently bridged from armature 38 to its left hand contact prevents packing of any transmitter connected to the primary winding of transformer 14 at the time the armature 38 opens 55 its left hand contact.

Two switches 47 and 48 are the switches referred to above as switches operable to selectively connect conductors 39 and 40, together, to transmitters 6 and 7. Switch 47 60 is comprised in telephone transmitting set 1 and has a pair of inner left hand alternate contacts operable to connect transmitter 6 to conductor 39, to complete the connection of the transmitter to the conductors 39 and 40.

Similarly, switch 48 is comprised in telephone transmitting set 2 and has a pair of inner left hand alternate contacts operable to connect transmitter 7 to conductors 39 and 40.

A normally deenergized receiver group 70 connecting relay, such as relay 49 and relay 50, is provided for each receiver group such as 3 and 4. The relay 49 when operated connects conductors 23 and 24 to conductors 51 and 52, respectively, which lead to receiver group 3. Similarly the relay 50, when operated, connects conductors 23 and 25 to conductors 53 and 54, respectively, which lead to receiver group 4.

A source of D. C., 55, symbolic of means comprising a storage battery, D. C. dynamo or the like, energizes relay 49 whenever the outer right hand contacts of switch 47 and the contacts of a receiver group selecting switch 56 in series therewith are closed, or whenever the outer right hand contacts of switch 48 and the contacts of a receiver group selecting switch 57 in series therewith are closed. The switches 56 and 57 are comprised in the telephone transmitting sets 90 1 and 2, respectively. The circuit for thus energizing relay 49 through switches 47 and 56 extends from the upper terminal of source 55 through the winding of relay 49, conductors 58 and 59, switch 56, outer right hand contacts of switch 47, and conductors 60 and 61 to the lower terminal of source 55. Similarly, the circuit for energizing relay 49 through switches 48 and 57 extends from the upper terminal of source 55 through the winding of relay 49, conductors 58 and 62, switch 57, outer right hand contacts of switch 48, and conductors 60 and 61 to the lower terminal of source 55. Thus, switch 56 and the contacts of switch 47 that are in series therewith are in parallel with switch 57 and the contacts of switch 48 that are in series therewith.

The source 55 energizes relay 50 whenever the inner right hand contacts of switch 47 and the contacts of a receiver group selecting switch 64 in series therewith are closed, or whenever the inner right hand contacts of switch 48 and the contacts of a receiver group selecting switch 65 in series therewith are closed. The switches 64 and 65 are comprised in the telephone transmitting sets 110 1 and 2, respectively. The circuit for thus energizing relay 50 through switches 48 and 64 extends from the upper terminal of source 55 through the winding of relay 50, leads 66 and 67, switch 64, inner right hand contacts of switch 47, and leads 60 and 61 to the lower terminal of source 55. Similarly, the circuit for energizing relay 50 through switches 48 and 65 extends from the upper terminal of source 55 through the winding of relay 50, conductors 66 and 67, switch 65,

inner right hand contacts of switch 48, and conductors 60 and 61 to the lower terminal of source 55. Thus, switch 64 and the contacts of switch 47 that are in series therewith 5 are in parallel with switch 65 and the contacts of switch 48 that are in series therewith.

From the foregoing description it will be clear that from any telephone transmitting 10 station, such as stations 1 and 2, any desired ones of the receiver groups such as 3 and 4 can be connected to auto-transformer 22.

With the system in the condition in which it is shown, if switch 47 be operated from 15 the position in which it is shown into its alternate position, its inner left hand contacts will connect telephone transmitter 6 to conductors 39 and 40 as noted above, and consequently the transmitter will be energized by direct current from source 26 and 20 will be operatively connected to transmit telephonic currents to the primary winding of transformer 14. The D. C. energizing circuit for the transmitter 6 will extend from the positive terminal of source 26, through 25 conductors 69 and 45, contacts 35 of relay 34, conductor 41, winding 16 of transformer 14, conductor 39, inner left hand contacts of switch 47, transmitter 6, conductor 40, left 30 hand contact of armature 38, conductor 43, winding 17 of transformer 14, and conductor 70 to the negative terminal of source 26. The circuit for transmitting telephonic current from the transmitter 6 to the primary 35 winding of transformer 14 will extend from the transmitter through inner left hand contacts of switch 47 to conductor 39, through winding 16, conductor 41, contacts 35 of relay 34, conductor 45, condenser 44, winding 17, conductor 43, left hand contact of armature 38, and lead 40, to the transmitter 6.

The telephonic currents thus transmitted to the primary winding of transformer 14 45 will be amplified by the amplifier system 5 and the amplified current will be delivered to auto-transformer 22. (Since contacts 33 and 35 short circuit the primary and secondary windings, respectively, of the feed-back 50 transformer 30, the feed-back path is ineffective under the conditions assumed.) Therefore, if any one of the receiver group 55 selecting switches, such as 56 and 64, in the telephone transmitting set 1 is operated, the corresponding receiver groups, such as 3 and 4, respectively, will receive the amplified telephonic current from auto-transformer 22. However the receiver 8 will be 60 cut out of circuit by the outer left hand contacts of switch 47, which maintains a gap in the conductor 52 at a point between receiver 9 and receiver 8 whenever switch 47 is in the condition alternate to that in which it is shown.

65 This disabling of receiver 8 when trans-

mitter 6 is conditioned to operate other receivers, such as receiver 9 of group 3 and receivers 10 and 11 of group 4, will be desirable in case, for instance, receiver 8 if it were not disabled would be more likely 70 than such other receivers to produce objectionable side tone in transmitter 6, for example because of closer proximity of receiver 8 than such other receiver to transmitter 6. 75

With the system in the condition in which it is shown, if switch 48 be operated from the position in which it is shown to its alternate position, its inner left hand contacts will connect telephone transmitter 7 to conductors 39 and 40 as noted above, and consequently the transmitter will be energized by direct current from source 26 and will be operatively connected to transmit telephonic current to the primary winding of 80 transformer 14. The D. C. energizing circuit for the transmitter 7 and the circuit for transmitting telephonic current from the transmitter 7 to the primary winding of transformer 14 will be the same as the corresponding circuits traced just above for transmitter 6, except that transmitter 7 and the inner left hand contacts of switch 48 will be substituted for the transmitter 6 and the inner left hand contacts of switch 47. 85 The telephonic current thus transmitted from transmitter 7 will be amplified by the amplifier system 5. Therefore, if any one of the receiver group selecting switches, such as 57 and 65, in the telephone transmitting set 2 be operated, the corresponding receiver groups, such as 3 and 4, respectively, will receive the amplified telephonic current from auto-transformer 22. However, the receiver 10 will be cut out of circuit by the outer 90 left hand contacts of switch 48, which maintain a gap in the conductor 53 at a point between receiver 11 and receiver 10 whenever switch 48 is in the condition alternate to that in which it is shown. The purpose in thus 100 disabling receiver 10 is to prevent it from causing objectionable side tone in transmitter 7. 105

Alarm signal transmitting sets such as 71 and 72 are provided, comprising switches 73 and 74, respectively, and switches 75 and 76, respectively. The alarm signal transmitting sets may have any desired locations relative to the telephone transmitting sets such as 1 and 2, but preferably each telephone transmitting set has an alarm signal transmitting set individual thereto and located thereat. Thus, the drawing indicates set 71 as adjacent set 1, and indicates set 72 as adjacent set 2. 115

To transmit alarm signals from set 71, switch 73 is operated from the condition in which it is shown to the alternate condition, and switch 75 is closed, these operations 120 causing the receivers such as 8, 9, 10 and 11 125

to emit a tone, as described hereinafter. Similarly, to transmit alarm signals from set 72, switches 74 and 76 are operated, causing the receivers to emit a tone, as described 5 hereinafter.

When switch 73 is operated, the outer right hand contacts thereof, which are in parallel with the series circuit comprising switch 56 and the outer right hand contacts 10 of switch 47, close an energizing circuit for relay 49, this energizing circuit being the same as that traced above for energizing relay 49 through the series circuit just mentioned, except that the outer right hand contacts of switch 73 are substituted for that series circuit.

Similarly, when switch 73 is operated, the inner right hand contacts thereof, which are in parallel with the series circuit comprising 20 switch 64 and the inner right hand contacts of switch 47, close an energizing circuit for relay 50, this energizing circuit being the same as that traced above for energizing relay 50 through the series circuit just mentioned, except that the inner right hand contacts of switch 73 are substituted for that series circuit.

The outer and inner right hand contacts of switch 74 are in parallel with the outer 30 and inner right hand contacts, respectively, of switch 73; so the energization of relays 49 and 50 can be controlled by switch 74 just as by switch 73.

From the foregoing description it will be 35 apparent that whenever a switch such as switch 73 or switch 74 in any alarm signal transmitting set such as 71 or 72 is operated, all of the receiver groups, such as 3 and 4, will be connected to the auto-transformer 22 by the receiver group connecting relays such as 49 and 50.

Whenever switch 73 is operated, a circuit for energizing relay 36 is closed by the outer left hand contacts of switch 73, this energizing circuit extending from the upper terminal of source 55, through conductor 77, winding of relay 36, conductor 78, outer left hand contacts of switch 73, and conductor 61 to the lower terminal of source 55. Relay 50 45 will also be operated whenever switch 74 is operated, since the series circuit consisting of conductor 79, outer left hand contact of switch 74 and conductor 63 is in parallel with that part 55 of the circuit just traced, consisting of conductor 78, outer left hand contact of switch 73 and conductor 60. Therefore it will be seen that relay 36 is energized whenever a switch such as switch 73 or switch 74 60 in any alarm signal transmitting set such as 71 or 72 is operated. By closing a switch such as 75 or 76 in any alarm signal transmitting set such as 71 or 72, the relay 34 can be energized. The energizing circuit 65 when switch 75 is closed extends from the

upper terminal of source 55, through the winding of relay 34, conductor 81, switch 75, and conductor 61 to the lower terminal of source 55; and the energizing circuit closed by switch 76 is the same, except that for the 70 circuit consisting of conductor 81, switch 75 and conductor 61 in series, there is substituted the parallel circuit consisting of conductor 82, switch 76 and conductor 63 in series.

As described above, the energization of 75 relays 36 and 34 as just mentioned converts the amplifier into an oscillator, disconnects the transformer 14 and source 26 from conductors 39 and 40, changes the setting of the potentiometer 15 and removes the short circuits from the feed-back path through transformer 30, so that the amplifier 12 is converted into an oscillator. Output current from the oscillator is amplified by amplifier 13 and delivered therefrom to the circuit 80 comprising transformer 20, auto-transformer 22 and the receiver groups such as 3 and 4.

If the transmission of such alarm signals is initiated at an alarm signal transmitting 90 set remote from a given telephone transmitting set when that telephone transmitting set is in use by an operator, that operator may be unaware that his transmitter has been disabled (disconnected from transformer 14 and source 26) unless some provision 95 is made to call to his attention the disabling of his transmitter; for when he operated his switch such as 47 or 48 he disabled any receiver local thereto in order to avoid producing objectionable side tone in his transmitter, as described above. Therefore, a relay 83 is provided for restoring all of the disabled receivers whenever the system is 100 operated to produce alarm signals.

When the relay is energized as described 105 hereinafter its right hand contact closes a circuit extending from the left hand armature of relay 49, through the right hand contacts of relay 83, and conductor 84, to a point in conductor 52 lying between the receiver 8 and the outer left hand contact of switch 47. This circuit is in parallel with the part of conductor 52 lying between the point just referred to and the left hand armature of relay 49, and therefore the gap 110 in conductor 52 is ineffective to disable receiver 8. Thus receivers 8 and 9 will be operated in parallel in spite of the open normal contact of switch 47.

When relay 83 is energized as just mentioned, its left hand contact closes a circuit extending from the right hand armature of relay 50, through the left hand contacts of relay 83, and conductor 85, to a point in conductor 53 lying between the receiver 10 and 115 the outer left hand contact of switch 48. This circuit is in parallel with the part of conductor 53 lying between the point just referred to and the right hand armature of relay 50, and therefore the gap in conductor 120 125 130

53 is ineffective to disable receiver 10. Thus, receivers 10 and 11 will be operated in parallel in spite of the open normal contact of switch 48.

- 5 The energization of relay 83 referred to above is effected when a switch such as 73 or 74 in any alarm signal transmitting set is operated. The circuit closed by switch 73 for energizing relay 83 extends from the 10 upper terminal of source 55, through the winding of relay 83, conductors 86 and 87, inner left hand contacts of switch 73, and conductor 61 to the lower terminal of source 55. The circuit which switch 74 can close, 15 for energizing relay 83, is the same as that just traced through switch 73, except that the path consisting of conductor 88, inner left hand contacts of switch 74, and conductor 63, and connected in parallel to the path 20 consisting of conductor 87, inner left hand contacts of switch 73, and conductor 60, is substituted for the latter path.

When an alarm tone is being sent from an alarm signal transmitting set, such as 71 or 25 72, the tone may be broken up to form, for instance, telegraphic code signals, by opening and closing the switch such as 75 or 76 at the station in use, in the general fashion in which a telegraph key is customarily 30 operated to transmit the dots and dashes forming telegraphic code characters.

A frequency of about 1200 cycles per second has been found satisfactory as the oscillation frequency of the amplifier 12 when 35 that amplifier is being employed as an oscillator; but of course the oscillation frequency may be set at any value suitable for the operation of the receivers.

As mentioned above, the setting of potentiometer 15 is controlled by the armature of 40 relay 37. This feature renders it possible to set the amplifier gain at the value which it is desired to maintain during telephonic transmission, by proper adjustment of the 45 tap conductor 89, and yet, by proper adjustment of the tap conductor 90, obtain the most favorable potentiometer setting for the oscillating condition of the amplifier.

By means of the tap conductors 24 and 25, 50 the connections of receiver groups to the auto-transformer 22 can be independently adjusted to give the most favorable operating conditions for transmission.

In operating the system to transmit speech, 55 from, say, transmitter 6 to receiver groups 3 and 4, an operator at transmitting set 1 closes switches 56, 64 and 47, and then talks into transmitter 6. The closure of switch 56 and the operation of switch 47 cause relay 49 to be energized over a circuit extending from the upper terminal of source 55, 60 through the winding of relay 49, conductors 58 and 59, switch 56, outer right-hand contacts of switch 47 and conductors 60 and 61, 65 to the lower terminal of source 55. Conse-

quently, relay 49 connects receiver group 3 to auto-transformer 22 through a circuit extending from tap conductor 24, through the left-hand contacts of relay 49, conductor 52, all receivers of group 3 in parallel excepting any local receiver such as 8, conductor 51, right-hand contact of relay 49, and conductor 23 to auto-transformer 22. Any receivers of receiver group 3, which are local to transmitter 6 (such as receiver 8), will 70 be omitted from the circuit just traced because the operation of switch 47 has opened conductor 52 at the outer left-hand normal contact of this switch.

The closure of switch 64 and operation 80 of switch 47, as mentioned above, cause relay 50 to be energized over a circuit extending from the upper terminal of source 55, through winding of relay 50, conductors 66 and 67, switch 64, inner right-hand contacts of switch 47, and conductors 60 and 61 to the lower terminal of source 55. Consequently, relay 50 connects receivers 10 and 11 in parallel with each other to auto-transformer 22, over a circuit extending 90 from tap conductor 25, through the left-hand contacts of relay 50, conductor 54, receivers 10 and 11 in parallel, conductor 53, the right-hand contacts of relay 50, and conductor 23 to the auto-transformer 22. 95

The operation of switch 47 as mentioned above causes transmitter 6 to be energized over a circuit extending from the positive terminal of source 26, through conductors 69 and 45, contacts 35, conductor 41, winding 16, conductor 39, inner left-hand contacts of switch 47, transmitter 6, conductor 40, left-hand contact of armature 38, conductor 43, winding 17, and conductor 70 to the negative terminal of source 26. 100

The speech currents generated by transmitter 6 energize the primary winding of input transformer 14, through a circuit extending from the upper terminal of transmitter 6, through the inner left-hand contacts of switch 47, conductor 39, winding 16, conductor 41, contacts 35, conductor 45, condenser 44, winding 17, conductor 43, left-hand contact of armature 38, and conductor 40 to the lower terminal of transmitter 6. 110

Speech currents induced in the secondary winding of transformer 14 pass through potentiometer 15 and cause voltage variations between the grid and filament of amplifier 12, the filament of amplifier 12 being connected to potentiometer 15 through the right-hand contact of armature 37. Amplified speech currents traverse the circuit extending from the anode of amplifier 12, through condenser 28, primary winding 19 of interstage transformer 18, and contacts 33 to the filament of amplifier 12. The speech currents induced in the secondary winding of transformer 18 are amplified by repeater 13 and delivered through trans- 125 130

former 20 to auto-transformer 22, and thence over the circuits traced above to receivers 9, 10 and 11.

When the operator at transmitter 6 has finished transmitting his message, he releases switch 47 which returns to its normal position, thereby restoring the system to its normal condition shown in the drawing, excepting that switches 56 and 64 remain closed. He may open these switches at the termination of his message, or may allow them to remain closed until occasion arises for him to transmit to one of the receiver groups 3 or 4 to the exclusion of the other group, when he will open the switch 56 or 64 corresponding to the group which is to remain idle.

If occasion arises for transmission of alarm signals from alarm signal transmitting set 72 at a time when an operator is transmitting through transmitter 6, the system is operated in the manner now to be described. The operator at set 72 closes switch 74. The closure of the inner and outer right-hand contacts of switch 74 shunts the inner and outer contacts, respectively, of switch 73, so that receiver groups 3 and 4 become or remain connected to auto-transformer 22 regardless of whether the operator at set 1 allows switches 56 and 64 to remain closed. Moreover, the closure of the inner left-hand contact of switch 74 causes energization of relay 83 over a circuit extending from the upper terminal of source 55, through the winding of relay 83, conductors 86 and 88, inner left-hand contacts of switch 74, and conductors 63 and 61 to the lower terminal of source 55. Consequently, the right-hand contacts of relay 83 shunt the outer left-hand contacts of switch 47, so that the latter contacts, even if opened, will be ineffective to disconnect receiver 8 from auto-transformer 22.

The closure of the outer left-hand contact of switch 74 causes energization of relay 36 through a circuit extending from the upper terminal of source 55, through conductor 77, winding of relay 36, conductor 79, outer left-hand contacts of switch 74 and conductors 63 and 61 to the lower terminal of source 55. Consequently, armatures 37 and 38 operate to their inner contacts. The operation of armature 37 changes the setting of potentiometer 15 from tap conductor 89 to tap conductor 90. The operation of armature 38 breaks the D. C. energizing circuit traced above for transmitter 6. This break is shunted by condenser 46, as described above. The operation of armature 38 also breaks the talking circuit, traced above, between transmitter 6 and transformer 14. The closing of the inner contact of armature 38 also closes a gap in a circuit to be traced presently.

65 The operator at set 72 then closes switch

76 while maintaining switch 74 closed. The closure of switch 76 energizes relay 34 over a circuit extending from the upper terminal of source 55, through conductor 77, winding of relay 34, conductor 82, switch 76, and conductors 63 and 61, to the lower terminal of source 55. Consequently, relay 34 opens the short-circuiting contacts 33 and 35. The amplifier 12 now oscillates, generating signaling currents, for instance of a frequency 75 of 1200 cycles per second, which are delivered through amplifier 13 and transformer 20 to auto-transformer 22, and thence to all of the receivers 8, 9, 10 and 11. The output circuit of the oscillator extends 80 from the anode through condenser 28, winding 19, and winding 29 to the filament. The input circuit of the oscillator extends from the upper side of condenser 32 and winding 31, through conductor 45, condenser 44, 85 winding 17, conductor 43, inner contact of armature 38, conductor 42, winding 16, and conductor 41 to the lower side of condenser 32 and winding 31. By opening and closing switch 76 while maintaining switch 74 90 closed, the operator at set 72 can cause the oscillator to deliver to the receivers a tone interrupted in accordance with a telegraphic code.

When the operator at station 72 releases switches 76 and 74, the system returns to its normal condition as shown in the drawing.

From the foregoing description of operations of the system to perform certain functions, the operation of the system to perform other functions will be apparent without further explanation.

The broad features of the invention are capable of embodiment in various widely 105 different forms without departing from the spirit of the invention as defined in the following claims.

What is claimed is:

1. A system comprising a receiver, means 110 for transmitting signals, switching means operable for preventing signals transmitted by said first means from returning to said first means through said receiver, and means for causing operation of said receiver while said switching means is in its operated condition.

2. A system comprising a receiver, means for transmitting signals, switching means operable for preventing signals transmitted by said first means from returning to said first means through said receiver, and means for causing signals to reach said first means through said receiver, while said second means is in its operated condition.

3. A communication system comprising a telephone transmitter, two receivers normally so connected together as to operate together, means operable to cause connection of said transmitter to one of said receivers 130

while the other receiver remains disconnected from said transmitter, a signal transmitting station, and means for operating said other receiver from said signal transmitting

5 station while said first mentioned means is in its operated condition.

4. A telephone and alarm signal system comprising a telephone transmitter, two receivers, means operable to cause connection 10 of said transmitter to one of said receivers and prevent the connection of said transmitter to the other receiver, a signal transmitting station, and means for operating both of said receivers from said signal transmitting 15 station while said first mentioned means is in its operated condition and both receivers are disconnected from said transmitter.

5. A telephone and alarm signal system 20 comprising two telephone transmitters, two receivers normally so connected together as to operate together, means operable to cause connection of one of said transmitters to one of said receivers while the other of said receivers remains disconnected from said one transmitter, means operable to connect said other transmitter to both of said receivers at once, an alarm signal transmitting station, and means for operating said other receiver from said alarm signal transmitting 25 station while said first mentioned means is in its operated condition.

6. A telephone and alarm signal system comprising two telephone transmitters 30 remote from each other, a group of receivers, means operable to cause selective connection of said transmitters to said receiver group, means operable in response to a given operation of said first means to cause one of said receivers to remain disconnected from the transmitter selected by said given operation of said first means while another of said receivers is connected to said transmitter by said given operation of said first means, an 35 alarm signal transmitter station, and means for operating both of said receivers from said alarm signal transmitting station while said first means is in its operated condition.

7. A system comprising an amplifier having 40 an input circuit and an output circuit a feed back path for connecting said output circuit to said input circuit to cause said amplifier to oscillate, and means for short-circuiting said feed-back path and prevent-

ing longitudinal transmission of waves from 55 said output circuit to said input circuit through said path.

8. A system comprising a signalling transmitter, an amplifier, said amplifier having an input circuit and an output circuit with a 60 feed-back transformer having a primary winding and a secondary winding for connecting said circuits, and said input circuit having a gain adjusting potentiometer, means normally short circuiting said primary winding, means normally short circuiting said secondary winding, and means for causing change in the setting of said potentiometer, and for causing said short circuits to be open while said potentiometer 65 is operating in its altered setting, to convert said amplifier into an oscillator for generating signalling currents.

9. A system comprising a signaling transmitter, an amplifier, having an input circuit and an output circuit with a common terminal, for repeating signals from said transmitter, a feed-back path connected in series with said output circuit, for connecting said output circuit to said input circuit 70 to convert said amplifier into an oscillator, said feed-back path having one end so connected to said common terminal as to be maintained at the potential of said common terminal while said amplifier is repeating 75 said signals from said transmitter, and means for short circuiting said feed-back path.

10. A system comprising a signaling transmitter, an amplifier, having an input 80 circuit and an output circuit, for repeating signals from said transmitter, said input circuit including a transformer having a primary winding and a secondary winding, a feed-back path for connecting said output 85 circuit to energize said primary winding, for converting said amplifier into an oscillator, and means for short-circuiting said feed-back path and preventing transfer of waves from said output circuit to said secondary 90 winding through the electrostatic capacities between said windings.

In witness whereof we hereunto subscribe our names this 23rd day of December A. D., 1924.

DONALD F. WHITING.
HUGH S. TAYLOR.
